UNITED STATES PATENT OFFICE.

FRED W. LEUTHESSE, OF CHICAGO, ILLINOIS, ASSIGNOR TO MONASH-YOUNKER COMPANY, OF CHICAGO, ILLINOIS, A CORPORATION OF ILLINOIS.

AIR-VALVE FOR RADIATORS.

No. 813,011.

Specification of Letters Patent.

Patented Feb. 20, 1906.

Application filed March 18, 1904. Serial No. 198,739.

To all whom it may concern:

Be it known that I, FRED W. LEUTHESSE, a citizen of the United States, residing at Chicago, in the county of Cook and State of Illinois, have invented certain new and useful Improvements in Air-Valves for Radiators, of which the following is a specification.

This invention relates to that type of air-valves for radiators in which a chamber of an outer shell or casing has located therein a rising and falling float, carried by an expandible stem and having at its upper end a stem-valve, which coacts with a seat around a vent-passage in a plug entered into the neck of the outer shell or casing and by which the outlet of the air is controlled. The outer shell or casing is entered into a base, having on one side a lateral inlet, which opens into the chamber of the outer shell or casing, and in the inlet and the shell or casing is a drain-pipe for returning the water of condensation back to the radiator.

The primary object of the present invention is to furnish a means for venting the valve in cases where the ordinary vent-passage is closed from any cause or in cases where a quick venting is necessary; and the invention consists in providing a vent-port at the base end of the valve as a whole, which port is in communication with the chamber of the main shell or casing and is controlled by a movable stem having an acting end to open and close the port; and the invention further consists in the features of construction and combinations of parts hereinafter described and claimed.

In the drawings, Figure 1 is a side elevation of the valve of the invention; Fig. 2, a sectional elevation of the same; Fig. 3, a detail in elevation of the lower end of the valve, showing the plug controlling the vent-port at the bottom of the valve in the base or cup thereof; and Fig. 4, a detail in cross-section through the nipple having the inlet-passage therein, the port at the lower end of the valve in the base or cup, and the controlling threaded plug for the port.

The valve is constructed with an outer shell or casing A, inclosing a chamber A' and having at its upper end a neck B, which is screw-threaded at its inner end and receives a plug b, in which is a chamber b' with a tapered seating-face, and the plug has a vent-passage b² opening into the chamber of the

neck through a square head b³, by means of which and a suitable key the plug can be adjusted, as required, and a flange v⁴ between the head and the plug proper abuts against the bottom wall of the chamber in the neck. A cap C, with a solid top c and a solid side wall c', enters onto the end of the neck, and the side wall has a recess c², into which a vent-port c³ opens from the chamber of the neck. A packing a² around the plug prevents the escape of air.

A float D, secured to the upper end of a receptacle-stem E by a socket d, is located in the chamber A', and the socket d has a valve-stem d' to coact with the valve-seat around the vent-passage of the plug. The outer shell or casing is entered into a cup or base F, which has a peripheral rim or flange f for the purpose, and the expandible stem is held against lateral play by a pin e in the cup or base. A drain-pipe G from the chamber A' has its lower end turned and extended through a nipple g on the base or cup, which nipple is for the purpose of attaching the valve to a radiator.

The base or cup has a downwardly-projecting wall H, having a screw-threaded hole h, with a chamber h² on one side of the wall for the hole and a chamber h³ on the other side of the wall for the hole, and the chamber h² has an end wall through which a port h' opens into the passage of the nipple g or the lower end of the chamber A' of the valve as a whole. The threaded hole h receives a stem I, having an exterior thread to fit the thread of the hole, and the outer or rear end of the stem has a head i corresponding to the head b³ and adapted to receive a key by means of which the stem I can be advanced and receded. The forward end i' of the stem is tapered for its point to enter the port h' and seat around the wall of the chamber h² and tightly close the port h' when the stem I is advanced and open such port when the stem I is receded.

The stem I with its seating end i' controls the venting of the valve at the bottom or lower end. The stem I when advanced for its acting or seating end i' to close the port h' vents the valve through the passage b² of the plug b, as usual; but with this passage closed or the failure of the float and its stem-valve to operate properly in venting or for a quick venting the stem I is turned to withdraw its acting or seating end i' from the port h', al-

lowing the air to escape through the port h' and a port i' in the wall H to the atmosphere, thus venting the valve and clearing the radiator of air without employing the float and its valve-stem for the purpose. The venting-port at the bottom of the valve in connection with its controlling-plug furnishes a ready and quick means for venting the valve, it only being necessary to turn the stem I sufficiently to withdraw its acting end and open the port h' for the air to escape through the port i' , and this venting of the valve does not impair or affect the efficiency of the float and its stem, provided the vent-passage b^3 is open and the float and stem are operative, simply furnishing an additional venting means for the valve, which can be used or not, as may be desired, as with the stem I advanced for its acting or seating end to close the port h' the valve will operate in the usual manner of float-valves. This additional vent for the valve will be found desirable for use in cases where the float and its valve-stem are inoperative or where the vent-passage b^3 is closed, and the additional vent does not change the general operations of the float and its stem-valve when operative and the vent-passage b^3 is open.

What I claim as new, and desire to secure by Letters Patent, is—

1. In an air-valve for radiators, the combination of a shell or casing inclosing a chamber having leading therefrom at its upper end a valve - controlled vent - passage, a base or cup into which is entered the lower end of the shell or casing, a central wall depending from the base or cup, a nipple projecting in line with the wall and furnishing an attachment for the valve to the radiator, the nipple having a passage in communication with the chamber of the shell or casing and the wall having a longitudinal passage with the port at the inner end thereof in communication with the passage of the nipple, and a movable stem operating in the passage of the wall and having an acting end controlling the port between the passage of the wall and nipple, substantially as described.

2. In an air-valve for radiators, the combination of a shell or casing inclosing a chamber having leading therefrom at its upper end a valve - controlled vent - passage, a base or cup into which is entered the lower end of the shell or casing, a central wall depending from the base or cup, a nipple projecting in line with the wall and furnishing an attachment for the valve to the radiator, the nipple having a passage in communication with the

chamber of the shell or casing and the wall having a longitudinal passage with a port at the inner end thereof in communication with the passage of the nipple and a port opening therefrom adjacent to its inner end, and a movable stem operating in the passage of the wall and having an acting end controlling the port between the passage of the wall and nipple, substantially as described.

3. In an air-valve for radiators, the combination of a shell or casing inclosing a chamber having leading therefrom at its upper end a vent-passage, a float located in the chamber and provided with a valve-stem controlling the vent-passage leading from the upper end of the chamber, an expandible stem on which the float is mounted, a base or cup into which is entered the lower end of the shell or casing, a central wall depending from the base or cup, a nipple projected in line with the wall and furnishing an attachment for the valve to the radiator, the nipple having a passage in communication with the chamber of the shell or casing, and the wall having a longitudinal passage with a port at the inner end thereof in communication with the passage of the nipple, and a movable stem operating in the passage of the wall and having an acting end controlling the port between the passages of the wall and nipple, substantially as described.

4. In an air-valve for radiators, the combination of a shell or casing inclosing a chamber having leading therefrom at its upper end a vent-passage, a float located in the chamber and provided with a valve-stem controlling the vent-passage leading from the upper end of the chamber, an expandible stem on which the float is mounted, a base or cup into which is entered the lower end of the shell or casing, a central wall depending from the base or cup, a nipple projected in line with the wall and furnishing an attachment for the valve to the radiator, the nipple having a passage in communication with the chamber of the shell or casing, and the wall having a longitudinal passage with a threaded section and with a port at the inner end thereof in communication with the passage of the nipple, and a stem having a threaded body operating in the threaded section of the passage in the wall and having an acting end controlling the port between the passages of the wall and nipple, substantially as described.
